UNITED STATES PATENT OFFICE.

F. ROBERT SEIDENSTICKER, OF MERIDEN, CONNECTICUT, ASSIGNOR TO THE
BRADLEY & HUBBARD MANUFACTURING COMPANY, OF SAME PLACE.

DESIGN FOR A FENDER.

SPECIFICATION forming part of Design No. 16,909, dated September 21, 1886.

Application filed July 26, 1886. Serial No. 209,179. Term of patent 7 years.

To all whom it may concern:

Be it known that F. ROBERT SEIDENSTICKER, of Meriden, in the county of New Haven and State of Connecticut, have invented a new Design for a Fire-Fender; and I do hereby declare the following, when taken in connection with accompanying drawing and the letters of reference marked thereon, to be a full, clear, and exact description of the same, and to which said drawing constitutes part of this specification, and represents a perspective view.

This invention relates to a design for a fire-fender; and it consists in the configuration and ornamentation, as shown in the accompanying illustration and hereinafter described.

The fender represents a base, A, with a parallel angular-shaped bar, B, at the top, and with a post, C, at each end. The posts are of right-angular shape at the top and bottom, with an intermediate section representing spiral

flutes. Midway of the length of the fender is an ornamental ring-shaped center piece between the base and upper bar, and a post, E, at each side. Each side of the center piece between the base and bar is a series of plain twisted spindles, all as shown in the accompanying illustration.

I claim—

The herein-described design for a fender, consisting of the base A, angular-shaped bar B above and parallel therewith, uprights C at each end, intermediate uprights, E; with a central ornament between them, and spindles at each side the center, between the uprights C and E, said spindles represented as twisted, as shown in the accompanying illustration.

F. ROBERT SEIDENSTICKER.
